CLAIM

I claim the ornamental design for a jersey, as shown and described.

DESCRIPTION

FIG. 1 is a perspective view of a jersey, showing my new design;

FIG. 2 is an enlarged front view of the claimed region of
FIG. 1;

FIG. 3 is an enlarged front view of the region denoted on
FIG. 2; and,

FIG. 4 is an enlarged perspective view of the region denoted on FIG. 2.

The broken lines are provided for environmental purposes only and form no part of the claimed design.

1 Claim, 4 Drawing Sheets
